UNITED STATES PATENT OFFICE.

ENRIQUE G. DOERING HARMSEN, OF HACIENDA SAUSAL, VIA TRUJILLO, PERU.

POCKET LEVEL.

Application filed September 24, 1920. Serial No. 412,596.

To all whom it may concern:

Be it known that I, ENRIQUE G. DOERING HARMSEN, a citizen of Peru, residing at Hacienda, Sausal, via Trujillo, Peru, South America, have invented new and useful Improvements in Pocket Levels, of which the following is a specification.

My invention relates to improvements in combination level and angle-measuring instruments.

An object of the invention is to provide an instrument of the type above referred to which can be folded to suitable size so that it may be conveniently carried, and one that will be large enough when placed in operation to give reliable results. A further object is to provide a compact assembly of a plurality of instruments, such as a compass, level, and an angle-measuring device in one structure which can be economically manufactured.

My invention consists of the novel arrangement and construction of parts described in the following specification, illustrated in the accompanying drawing and claimed in the appended claims.

In the drawings, Figure 1 is a side elevation of the preferred form of my invention and shows the movable arm in different positions and the quadrant inoperative and closed positions.

Fig. 2 is a top plan view of the parts shown in full lines in Fig. 1.

Fig. 3 is a vertical longitudinal section through the arm and base of my improved combination instrument showing the arm in one of its open positions.

Fig. 4 is a vertical transverse section through the movable arm, level, telescope and base.

Figs. 5 and 6 are vertical sections of the telescope showing the eye piece and cross-hairs, respectively.

The numeral 10 designates a base and it will be understood that this base as well as other parts of the structure of this device may be of any suitable material or materials, such as wood, aluminum, bronze, brass or steel. One end of this base is cut away so as to form stepped portions 11 and 12, the step 12 having the limiting edge 13 for a purpose that will hereinafter appear.

The opposite end of the base is also cut away so as to form a recess in which the projecting end 14 of an arm 20 is pivotally

supported by means of a bolt 15 passing through apertures in the projecting end 14 of the arm and recessed portion 16 of the base.

A nut 17 having a knurled flange is mounted upon the threaded end of the bolt for releasing the arm for rotational movement and for locking said arm in adjusted positions. The nut 17 is preferably internally recessed and in this recess is placed a coil spring 18 which bears against the end 14 and the interior of the flange for yieldingly holding the arm 20 in the desired position with a force depending for intensity upon the position of the nut 17 on the bolt 15.

The end 14 of the arm 20 is an annular enlargement of the body of the arm, the lower surface of which, when in closed position, is in the same horizontal plane as the axis of the bolt 15, so that said arm, when in folded position will contact with the upper surface of the base 10. The arm 20 is shorter than the base, but to its free end is secured a slotted pointer 21 having a reduced end 22 that fits into a corresponding opening in the arm 20 and is locked thereto by means of a screw 23. When in locked position the lower surface of the pointer forms a continuation of the lower surface of the arm.

The arm 20 is provided with an opening the upper diameter of which is reduced by the flange 24. A level tube is inserted through the bottom of the opening in the arm. The level tube is retained in place by the plates 25 and screws 26. The top and bottom of the tube are marked with lines whereby the relative position of the bubble can be readily ascertained when viewed from below as well as from above.

The arm 20 has a recess in its upper surface of dimensions sufficient to receive a compass case 30 provided with a transparent top-plate 31 and containing a magnetic needle 32 and graduated dial 33. The compass case 30 is retained in place by means of the threaded stud 34 projecting therefrom and engaging the arm 20.

The movable arm is also equipped with a sighting tube 35 which is secured to one side of the arm 20 preferably by means of the stirrups 36 and screws 37 extending through ears on said stirrups and engaging the arm 20. The sighting tube is provided

with an adjustable eye piece 38 having a plate 39 with an aperture 40^a therein and a disc 41 carrying cross-hairs or lines etched on glass so that the object sighted may be definitely located in the field of view of the telescope. Care must be exercised in assembling the tube to the arm in order that the axis of the tube may be exactly parallel to the axis of the movable arm and pointer.

10 To the recessed portion 11 of the base 10 is pivotally secured a graduated arc 40, the center of which is the point at which the movable arm 20 is pivoted to the base 10. This arc is preferably made of metal and 15 adapted to be received within the slot of the pointer 21. One end of the arc 40 is triangular in shape and apertured so as to receive a bolt 41^a which is threaded at one end for the nut 42. The nut 42 is formed 20 with a knurled flange similar to the flange of nut 17 previously described. To the base 10 is secured a pin 43 which projects outwardly a sufficient distance to contact with one of the sides of the triangular end of the 25 arc shaped strip 40 in order to limit the movement of the arc to the correct position.

The base 10 has a bore 46, of which the axis is in the same plane with the longitudinal axis of the tube 35 but perpendicular thereto, when the movable arm is in zero position. A circular bed plate 50 is provided with a central hole 51 adapted to receive the vertical pivot pin (not shown) of a tripod. This bed plate is graduated 35 into 360° and for measuring horizontal angles the edge 13, which lies in the same vertical plane as the center of hole 51 and axis of the tube 35, is the index mark or pointer for indicating the reading on the 40 graduated bed plate. In view of the fact that the 360° circle is rather large to carry in the pocket, it is divided into two sections, and these sections are connected so as to fold along the line indicated at 52 in Fig. 2 45 preferably by suitable hinges (not shown). The bed plate is also provided with the holes 44, 45 through which screws or bolts may be inserted for fastening the circle 50 against rotation on the head of the tripod.

50 The instrument can be used to measure the inclination of any surface by placing the base in contact with the surface and rotating the movable arm 20 until the air bubble is in the center of the level tube. The 55 pointer will then indicate the correct degree of inclination on the graduated arc which has previously been placed in operative position. In folded position the arm 20 is horizontal and the arc 40 is folded through 60 the slot of pointer 21 until it engages one of the upper edges of the arm as shown by dotted lines in Fig. 1. It will be seen that this arrangement gives a compact combination instrument that can be readily carried 65 about.

When the bed plate 50 is used, it is carried in folded position and, when the destination is reached assembled on a tripod by means of screws passing through holes 44 and 45. The pivot pin of the tripod (not shown) is also inserted through hole 51 of the bed plate and hole 46 of the base which is superposed on the bed plate. The base and arm may now swing about the pivot for measuring the horizontal angle between objects sighted through the telescope 35, the reading being taken from the positions of the edge 13 of the base relatively to the 75 graduations on the base plate 50.

This instrument provides a small, compact, portable device for use by engineers, topographers, architects, masons, mechanics, carpenters and the like for measuring inclinations and angles and for ascertaining distances and heights. The making of this 80 instrument in the form of a small toy for the education and amusement of children is also contemplated.

The arm 20 in conjunction with the base may also be used as a draftsman's triangle 90 in translating different measured angles to paper.

Having thus described my invention, what I claim as new and desire to secure by Letters Patent, is:—

95 1. In a combination level and angle measuring instrument, a base having recesses at opposite ends, an arm pivotally secured to the base in one of said recesses, a level carried by said arm, a graduated arc-shaped strip pivotally attached to the base in the other of said recesses and adapted to be moved to operative or folded position, and a pointer fixed to said arm and provided with a slot to receive said strip when in folded position.

2. In a combination level and angle measuring instrument, a base having a recess at each end, an arm pivotally secured to the base in one of said recesses, a level carried by said arm, a graduated arc-shaped strip pivotally attached to the base in the other of said recesses and adapted to be moved to operative or to folded position, a slotted pointer carried by said arm for receiving said strip, and a pin projecting from said base for limiting the outward movement of said strip in the operative position.

120 3. In a combination level and angle measuring instrument, a base means for measuring vertical angles pivotally supported by said base, a level carried by said means and a graduated plate upon which said base is pivotally mounted, said base having a recess of which one edge cooperates with the graduations on said plate for indicating the angular position of the base on said plate.

125 4. In a combination level and angle measuring instrument, a base, means for measuring vertical angles including an arm and an

arc-shaped graduated strip pivotally supported by said base, a pointer carried by said arm and associated with said strip, a level and a telescope carried by said arm, said 5 telescope having its optical axis parallel to the axis of the pointer.

5. In an instrument of the type described, a graduated bed plate, a base pivotally mounted on said bed plate, and having 10 means cooperating with the graduations on the bed plate, a movable arm carried by said base adapted to be folded into contact therewith, a level carried by said arm, a graduated arc-shaped strip over which said arm 15 is movable for indicating vertical angles, and a telescope mounted on said arm having its optical axis in the same plane with the vertical axis of the pivotal support of said base, whereby after the leveling of the arm 20 and base, objects may be sighted through the telescope and the horizontal angle between said objects determined by the corresponding readings between the base and the 25 graduations of the bed plate, and objects of different elevations may be sighted and the

vertical angle between them determined by the corresponding readings between said arm and the graduations on said arc.

6. In an instrument of the type described, the combination of a base, a graduated arcuate strip pivotally connected to and adapted to be folded on the base, a horizontal graduated plate on which the base is pivotally supported, means carried by said base and associated with the graduations on said plate for indicating the angular position of said base with reference to said plate, an arm pivotally connected to said base, and means carried by said arm and cooperating with the graduations on said strip to indicate the angular position of said arm relatively to said base.

In testimony whereof I have hereunto set my hand in presence of two subscribing witnesses.
